UNITED STATES PATENT OFFICE

HARRY GLAENZER, OF PHILADELPHIA, PENNSYLVANIA

END FRAME OF LOCOMOTIVES

Application filed October 30, 1928. Serial No. 316,001.

My invention relates to certain improvements in end frames of locomotives.

The object of my invention is to make an integral casting containing a cylinder saddle, center pin or guide, equal beam fulcrum, draw pin pocket, and bumper and deck. This object I attain in the following manner, reference being had to the accompanying drawings, in which:

10 Fig. 1 is a plan view;

Fig. 2 is a longitudinal sectional view on the line 2—2, Fig. 1;

Fig. 3 is a front view of the frame;

15 Fig. 4 is a view of the rear end of the structure;

Fig. 5 is a sectional view on the line 5—5 of Fig. 2; and

Fig. 6 is a sectional view on the line 6—6 of Fig. 2.

20 Referring to the drawings, 1 is the cylinder saddle, having side surfaces 2—2 to which the cylinder structures are bolted. In the saddle are formed pasageways 3—3 through which high pressure steam passes to the cylinders in the direction of the arrow, Fig. 2. A single pasageway is divided into two pasageways leading to the upper surface of the saddle, so that the necessary pipes leading to the cylinders can be coupled thereto 30 in any suitable manner.

At the forward end of the structure is the bumper 4, and under the bumper are the draw pin pockets 5. This portion of the structure is reinforced by ribs 6 and 7. 8 is 35 the center pin bearing and this may be arranged to receive a center pin, or the center pin may form a part of the structure, depending somewhat on the type of the locomotive to which the invention is applied.

40 It will be noticed that the structure is hollow, so as to make it as light as possible, while openings 9—9 are formed in the structure for the purpose of reducing its weight.

Extending from the saddle are four longitudinal ribs 10 which add strength and rigidity to the structure, and extending through the centre of the cylinder saddle is a strengthening partition 11 which is perforated in order to lighten the same and to allow for reaming operations, the openings in the struc-

ture being such that access may be had to the interior thereof.

At one end of the structure is a depending bracket 12, which forms the bearing for a radius bar, and directly in front of this bearing are two depending plates 13—13, which form the bearing for the equalizing beam, the pivot pin for the said beam passing through openings 14.

15 are brackets to which the waist-sheets 60 of the locomotive are secured.

In this end of the structure are transverse partitions 16, shown by dotted lines in Fig. 1 and full lines in Fig. 6, and extending from the saddle structure to the bumpers are internal ribs or partitions 17. These latter partitions as well as the partitions 16 have openings 18 at intervals. By this construction, the structure is provided with reinforcing ribs at different points where additional 70 strength is desired.

The frame of the engine is carried through a portion of the saddle and fits against the surface 19, Fig. 5, making a neat fit, while horizontal keys may be located between the 75 projections on the frame and the cylinder saddle.

This end frame may be located at either end of the locomotive, depending upon the particular type of locomotive under construction. 80

I claim:—

1. A locomotive end frame made in a single casting and consisting of a saddle in which are live steam passages, said saddle portion having side surfaces to which the cylinders 85 are attached, and having surfaces below the cylinder surfaces for attachment to the side frames of the locomotive; an integral bumper at the forward end of the structure having integral draw pin pockets thereunder; and a 90 centre pin bearing between the bumper and the saddle.

2. A locomotive end frame made in a single casting and consisting of a cylinder saddle in which are live steam passages; a deck; a 95 bumper at the end of the deck; centrally located plates depending from the saddle part of the structure forming the bearings for an equalizing beam; a bracket at the back of the plates, forming a bearing for a radius bar, 100

said saddle having surfaces at each side to which the cylinders are secured; and surfaces below the cylinder surfaces to which the side frames of the locomotive are secured.

- 5 3. A locomotive end frame made in a single casting and having a centrally located cylinder saddle at one end thereof, said saddle having a live steam passage with two branches extending to the upper surface of the casting,
10 said structure having surfaces at each side to which the cylinder structures are secured, the frame being offset below said side surfaces and having surfaces for attachment to the side frames of the locomotive; and a bumper
15 at the opposite end of the end frame.

HARRY GLAENZER.
